UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,409,425.

Specification of Letters Patent. Patented Mar. 14, 1922.

Application filed October 4, 1921. Serial No. 505,262.

To all whom it may concern:

Be it known that I, EDWARD S. STIMPSON, a citizen of the United States, residing at Hopedale, in the county of Worcester and 5 State of Massachusetts, have invented an Improvement in Warp Stop Motions for Looms, of which the following description, in connection with the accompanying drawings, is a specification, like characters on the 10 drawings representing like parts.

This invention relates to warp stop motions for looms, whereby upon the occurrence of a warp fault such, for instance, as breakage or undue slackness of a warp 15 thread, the loom is stopped.

It is an object of the present invention to provide a warp stop motion or mechanism which shall be simple in construction, effective in operation in response to a warp fault, 20 and wherein the parts are so organized and combined that a number of advantages, as hereinafter described, may be secured.

It is desirable at times to run the loom without causing the stoppage thereof due to 25 a warp fault. These occasions arise, for instance, when a new warp is placed in the loom. Under this condition it is desirable to run the loom for a time to condition the warp and bring the warp threads into uniform tension and arrangement for the weaving 30 operation. The occasion for running the loom without stopping due to a warp fault, may also arise where there has been a "smash" or other condition that disturbs the 35 general arrangement and tension of the warp threads. An important feature of the present invention, therefore, consists in a warp stop motion wherein the feeler may be moved at will from operative position with 40 respect to the drop wires, so that without disturbing other portions of the warp stop motion, the loom may continue to run even though some of the warp threads are too slack or become broken.

45 Where the warp stop motion proper is placed between the shedding mechanism or heddles and the rear of the loom, the character and construction of the warp stop motion will determine to a large extent the size 50 of the warp beam, or the amount of warp

permissible to be wound upon the beam. Another important feature of the invention, therefore, consists of a warp stop motion which is compact and which shall occupy a minimum amount of space fore and aft of 55 the loom, and wherein the construction is such that it will not interfere with or materially limit the size of the warp beam or the amount of warp wound upon the beam.

The above and other novel features and 60 new combination of parts will best be made clear from the following description in connection with the accompanying drawings, which show one good, practical form of means for carrying the various features of 65 the invention into practical effect.

This application is a continuation in part of the copending application of Edward S. Stimpson, Serial No. 474,368, filed June 2, 1921. 70

In the drawings:—

Figure 1 is a partial side elevation of the loom provided with a warp stop motion embodying the present invention, some of the parts being broken away to show others beyond; 75

Fig. 2 is a detached detail showing more particularly a train of mechanism for effecting loom stoppage when the detecting movement of the feeler is arrested by a drop wire; 80

Fig. 3 is an enlarged perspective view showing the feeler removed from its operative relation with the drop wires and in the act of being hung upon suitable supports conveniently provided on the arch of the loom, 85 some of the drop wires being omitted for clearness of illustration;

Fig. 4 is an enlarged perspective view showing portions of the warp stop motion proper and the feeler removed from operative position with relation to the drop wires; 90

Fig. 5 is an enlarged sectional view through the warp stop motion proper, showing more particularly the relation of the feeler, drop wires and associated parts when 95 they are in operative relation, and the adjusting means for the warp supports; and

Fig. 6 is an enlarged detail perspective view of a portion of the warp stop motion proper, and the adjustable warp support. 100

As indicated in Fig. 1, the warp stop motion proper is located between the shedding mechanism or heddles and the rear of the loom, and is associated with the mechanism 5 actuated by the lay when the feeler is arrested in its detecting movement by a drop wire, to thereby knock-off the shipper and effect loom stoppage. The illustrated form of the mechanism between the warp stop 10 motion proper and the shipper constitutes a good, practical train of mechanism for effecting the desired purpose, but it is to be understood that the invention is not restricted thereto, but that the warp stop motion proper may be associated with any desirable train of mechanism which will serve to bring the loom to rest when a detecting movement of the feeler is stopped by a drop wire.

20 The term "drop wire" is herein used in its broad sense to designate the elements which are normally supported by the warp threads during weaving. The drop wires shown are formed of or stamped out of sheet metal.

25 The loom frame 1 may be of usual construction provided with a suitable support at the rear portion thereof for the warp beam 2 on which the warp threads are wound. Pivotaly mounted at 3 is the shipper 30 per 4 which, when the loom is running, may be held in the usual shipper notch. Pivotaly mounted at 5 on the loom frame is the knock-off lever 6, one end 7 of which bears against the shipper and another portion is 35 connected at 8 to a link 9 extending rearwardly of the loom, the construction being such that rearward longitudinal movement of the link 9 will serve to turn the knock-off lever 6 on its pivotal support and thereby 40 detach the shipper from its holding notch to effect loom stoppage.

The link 9 has its rear end connected at 10 to an arm 11 pivotally supported at 12 by a bracket 13, Fig. 2, secured to the loom 45 frame. Mounted for rocking movement on the arm 11 is the dog 14, Fig. 2, having a pin 15 which extends into the slot 16 of a controller 17 secured to the rocker 18 mounted in a bearing at the upper portion of the 50 bracket 13. The lay 19 has connected thereto the bunter 20, preferably adjustable, as by the slot and bolt connection 21, Fig. 2, the construction being such that should the end 55 of the dog 14 be in position for engagement with the bunter 20 as the lay moves back, the rocker arm 11 will be moved backwardly and thereby exert a pull upon the link 9 to knock-off the shipper and stop the loom. The mechanism so far described is or 60 may be of usual construction, such for instance, as shown and described in the patent to G. B. Ambler, No. 885,130, dated April 21, 1908, but so far as the novel features of the present invention are concerned, other 65 forms of transmitting mechanism may be

employed between the warp stop motion proper and the loom stopping mechanism for effecting loom stoppage when the feeler is arrested in its detecting movement by a drop wire.

70 Extending from the rocker 18 is an arm 22, which is connected at 23 to a link 24, the upper portion of which is jointed at 25 to a rocker arm 26 secured to and extending from the rock shaft 27. The rock shaft 27 has 75 secured thereto an arm 28 to which is connected the link 29 which extends downwardly as indicated in Fig. 1, and is pivotally connected at 30 to a cam follower 31 pivotally supported at 32. Adjustably supported upon the rocker arm 26 is the weight 33 which serves to hold the end of the cam follower 31 against the cam 34, Fig. 1, which is conveniently secured to or operatively connected with the lower or cam 85 shaft 35. From the mechanism thus far described it will be apparent that as the cam 34 rotates, the rock shaft 27 will be given a rocking movement, and so long as rocking movement is unarrested, the dog 14 will be 90 moved out of the path of the bunter 20 as the lay moves back.

95 Secured to each side of the loom frame is a bracket or support 36, Figs. 3 and 4, having a slot 37 to which is adjustably connected the side brackets 38 which, in the present instance, constitute the support for the warp stop motion proper. The side brackets 38 have lateral extensions 39 slotted at 40, and a bolt 41 adjustably secures each 100 side bracket to its associated supporting bracket 36.

The rock shaft 27, hereinbefore described, extends transversely of the loom and is conveniently supported for rocking movement in bearings 42 formed in the side brackets 38.

Extending between the side brackets 38 are the warp supports 43, the ends of which may be received in socket members 44 extending inwardly from each of the brackets 38, Figs. 3 and 4. In the present instance, four warp supports 43 are shown, but obviously the number of such supports may be varied to suit conditions of use. The warp 110 threads *a* pass from the warp beam 2 over the warp supports 43 to the shedding mechanism or heddles 45 which may be of usual construction and operated in a well-known manner to form the shed. From the heddles 115 45 the warp threads pass through the reed 46 to the fell of the cloth at 47, from which point the cloth is led forwardly to any usual form of takeup.

120 Supported above the plane of the warp threads are the drop wire guides 48. In the present instance the drop wire guides 48 are supported by the side brackets 38, each of which has upwardly-extending lugs 49 corresponding in number to the number of drop 130

wire guides, four being shown in the present instance, but obviously any desired number may be employed. The drop wire guides 48 are detachably held to the side brackets 38 by clips 50, Fig. 4, each having a slot 51, Fig. 4, through which passes the securing bolt or screw 52. Adjacent the end portion of each of the drop wire guides 48 the clips 50 have an upstanding portion 53 and a flange 54 which overlies the top of the drop wire guides, the construction being such that when the clips are moved into contact with the end portions of the drop wire guides they serve to hold the drop wire guides effectively in their guiding position; and when the clips 50 are released by their clamping screws, they are adapted to be moved backwardly to free the drop wire guides for ready removal from the side supporting brackets 38.

Mounted upon each of the drop wire guides 48 is a series of drop wires 55 which are normally supported by the warp threads during weaving. The drop wires may be variously formed, but in the present instance of the invention each drop wire is provided with a slot 56 through which is passed a drop wire guide for directing movement of the drop wire when it is released by a broken or too slack warp thread. Each of the drop wires has an enlarged portion 57 and as shown, the rear portions of the drop wires of the several rows all face in the same direction. As shown, each of the drop wires has the lower leg portion 58, the upper end wall of which rests upon a warp thread and serves to maintain the drop wire in its raised position during weaving. In certain aspects of the invention the particular form of drop wire is immaterial, but the construction shown, which is known as the "hairpin" drop wire, is found to be preferable for certain purposes.

Associated with the drop wires is a feeler which is given a detecting movement and which, when arrested by one of the drop wires, effects loom stoppage. As before mentioned, it is desirable at times to run the loom without stopping due to a fault in the warp, and for this purpose the present invention provides a feeler mechanism which may be moved from operative relation with the drop wires at will, so that even though a warp thread should break or one or more of such threads become too slack for good weaving purposes, the loom will continue to run so long as the feeler mechanism is not in operative relation with the drop wires. In carrying this feature of the invention into practical effect, the feeler for a row of drop wires is supported above the plane of the warp threads and for detecting movement toward and from the drop wires. In order that it may be readily removed from operative relation with the drop wires with-

out disorganizing the warp stop motion, the feeler is connected with its actuating mechanism in a manner to permit the feeler to be moved in a direction heightwise of the drop wires out of operative relation therewith. 70

In the particular construction shown for carrying out this feature of the invention, the supporting brackets 38 are each provided with a guiding support 59 which may be conveniently formed as part of or be connected to the brackets 38. In the present instance the guiding supports 59 are cast integral with the side brackets and afford a support on which the side members 60 of a feeler carrier may rest. Extending between 75 and secured to the side members 60 of the feeler carrier are the feelers 61, corresponding in number with the number of rows of drop wires. The side members 60 of the feeler carrier are provided with lug portions 80 85 62, Figs. 3 and 4, to which are secured the feelers 61 by means such as the securing bolts and nuts 63, the construction being such that they may be readily secured to or removed from the side members of the feeler 90 carrier. Each side member 60 of the feeler carrier has an extending portion 64 which may be connected to the feeler actuator, presently to be described, by means of a pin 65 extending laterally from each of the extending portions 64, whereby the feeler carrier may be given a reciprocating movement on its guiding supports 59.

Extending from the rock shaft 27 is the arm 66 having a bifurcated upper end portion 67 which receives the pin 65 extending from the feeler carrier, the construction being such that upon rocking movement of the rock shaft 27, the feeler carrier and the feelers carried thereby, will be given a 100 reciprocating movement, and the feeler carrier and feelers may be readily removed at will from operative relation with the drop wires by a movement of the feeler carrier and feelers in a direction heightwise of the 105 110 drop wires.

As a preferable form of construction, the side members 60 of the feeler carrier have end bearing portions 68 which rest upon the guiding supports 59, while the other end 115 portion of the side members of the feeler carrier may be supported by the bifurcated end 67 of the feeler actuator. From this construction it will be apparent that the weight of the feeler carrier and feelers is 120 supported at one end by the guiding supports 59, and at the other end by the bifurcated end 67 of the feeler actuator.

When the feeler and feeler carrier are removed from operative relation with the 125 drop wires, which is effected manually by the loom attendant, it is desirable that the feeler carrier and the feelers be supported within convenient reach of the attendant so that they may be replaced after the warp 130

threads have become conditioned properly for weaving purposes. As a convenient means to this end, the arch 69 of the loom, Fig. 3, may be provided with supporting 5 rests 70 having end portions 71 for receiving the pins 65. This construction affords a convenient means for supporting the feeler mechanism when it is removed from operative relation to the drop wires, but while 10 it possesses advantages in this connection, it is not an essential, as the feeler mechanism may be otherwise supported or laid aside.

The feelers 61 are supported by the feeler 15 carrier above the warp threads, thereby lessening the space occupied by the feeler mechanism proper in proximity to the warp beam, and permitting a ready movement of the feelers from their operative relation with 20 the drop wires either to permit the loom to be run without stopping, due to a warp fault, or to permit the ready removal of the drop wires, drop wire guides and warp threads in removing and placing a new 25 warp.

The feelers 61 are supported above the plane of the warp threads in an inclined position, thereby enabling the feelers to be formed of sufficiently heavy metal or stock 30 to withstand the checking action of the drop wires without bending; and such inclined position of the feelers economizes the space occupied by the feeler mechanism fore and aft of the loom and prevents the accumulation 35 of lint upon the feelers, which might otherwise interfere with the delicate operation of the mechanism. The detecting portion 72 of each feeler which engages a drop wire when it is released by a broken 40 or too slack warp thread, is preferably beveled with respect to the main body of the feeler, as indicated in Fig. 4, to present a substantially vertical wall to act upon the vertical edge of the drop wire. The inclined relation of the feelers with respect to 45 the lengthwise dimension of the drop wires is conveniently secured by forming the supporting face 73 of the lugs 62 inclined, as indicated in Fig. 4.

50 It is sometimes desirable to brace the feeler or feelers between the ends thereof in order to impart stability; especially is this the case where the feeler is employed in what is known as a "wide" loom. In such 55 cases the side members 60 of the feeler carrier may be further braced and secured together by an angle bar 73 which may conveniently be formed as part of one of the feelers, as indicated in Fig. 3. Secured to 60 the angle bar 73 is a lug 74, Fig. 3, to which is secured a feeler brace 75, the lower edge portion of which is notched as at 76, Fig. 3, to receive the upper edge portion of each of the feelers 61. The number of braces 75 65 may be varied.

It is common in warp stop motions or mechanisms to provide a strengthening brace for the drop wire guides, but in the present invention the brace for the drop wire guides is of novel construction, and is 70 arranged so that the braces may be adjusted laterally at one end in order to converge correspondingly with the warp threads toward the front of the loom. In the present instance of the invention, the drop wire 75 guide braces are mounted for transverse adjustment upon the brace-supporting rod 77, Fig. 3, which may be conveniently supported in bearings 78 provided in the side brackets 38, and if desired, the supporting rod may 80 be secured in position by a set screw 79, at each end.

Mounted for transverse adjustment on the supporting rod 77 are the collars 80, of which there may be one or more, three being 85 shown in the present instance of the invention. These collars may be secured in adjusted position on the rod 77 by appropriate securing means such as the set screws 81. Extending from each of the collars 80 is a 90 lug 82 having a bearing to receive the stem 83 of the drop wire guide brace, which is preferably formed circular in cross section for ready swinging adjustment in the bearing 82. Each of the collars 80 has a set screw 95 84, whereby the associated stem 83 may be secured in adjusted lateral swinging position.

Mounted upon each of the stems 83 is a drop wire guide brace 85, which has a series 100 of notches 86 corresponding to the number and for the reception of the drop wire guides 48. The slots 86 are of sufficient size with relation to the dimensions of the drop wire guides, to permit the brace or braces 85 to 105 be adjusted laterally at one end to correspond to the convergence of the warp threads toward the front of the loom, as indicated in Fig. 3. In the present instance of the invention, the braces 85 are 110 connected to their supporting stems 83 by the heads 87 and clamping bolts 88, but these details may be varied within the true scope of the invention.

In weaving some kinds of fabrics, it is 115 desirable to vary the position of the warp supports, for instance, as in adapting the warp stop motion to a loom for weaving Marquisette or cross-woven fabrics. To this end, as indicated in Figs. 5 and 6, the 120 warp supports 43 may be carried in sockets 89 formed in an adjustable member 90 which will be made separately from the side brackets 91, similar in all other respects, however, to the side brackets 38 already described. The adjustable members 90, one at each side of the loom, have lug portions 92 which extend through the openings 93 formed in the associated bracket 91, as indicated in Fig. 6; and between the lug 92 and 131

the outstanding portion of the bracket 91 is interposed an adjusting screw 94, the construction being such that when the members 90 are free for adjusting movement, they 5 may be either raised or lowered in accordance with the character of the fabric being woven, by manipulation of the adjusting screw 94.

The members 90 which sustain the warp 10 supports, may be clamped in their adjusted position by means of a clamping bolt 95, Fig. 6, one of which passes through each of the side brackets 91 and enters a slot 96 formed in the associated member 90.

15 Should the rock-shaft 27, which constitutes part of the actuator for the feeler, be mounted on the adjustable side members 90 as indicated in Figs. 5 and 6, the present invention contemplates that the connection 20 between the feeler and the actuator shall be such that upon adjustment of the warp supports, the same amplitude of feeler movement may be maintained. To this end the pin 65 which engages the bifurcated end 25 67 of the arm 66 which projects from the rock-shaft 27, is carried by a plate 97, Figs. 5 and 6, which is adjustably secured to the projection 64 extending from the side members 30 of the feeler carrier. In the present instance the plate 97 carries the pin 65 and is provided with a slot 98, Fig. 5, through which passes the securing bolt 99 which adjustably secures the plate 97 to the projection 64. The construction is such that when 35 the warp supports are adjusted with their side members 90 up or down, the plate 97 may be correspondingly adjusted to maintain the same amplitude of movement of the feeler carrier and feelers, which are reciprocated by the rocking arm 66.

In the construction shown, the feelers are mounted or supported in an inclined position relative to the lengthwise dimension of the drop wires, and such construction is of 45 advantage in economizing the fore and aft space in the loom; but in certain aspects of the invention, the feelers may be otherwise related to the drop wires, and the drop wires themselves while shown as of the "hair-pin" 50 type, may be of different construction.

The construction shown and described constitutes a good, practical form of the present invention; is simple and efficient in operation; and by combining the parts in the 55 relation described with the feelers above the plane of the warp threads, not only does the warp stop motion not materially interfere with the size of warp beam or the amount of warp wound on the beam, but the 60 feelers themselves are rendered readily accessible and removable from operative relation with the drop wires by the loom attendant when it is desired to run the loom without stopping, due to a warp fault or when 65 a warp is to be removed or placed in the

loom. The reciprocating movement given to the feeler or feelers toward and from the drop wires in a path above the warp threads, and by an actuator, preferably at each side of the loom, enables the feeler 70 mechanism including the feelers and feeler carrier, to be made of sufficient rigidity to withstand the arresting action of the drop wire without flexing or bending the feeler, a condition which may be further insured in 75 case the feelers are supported in the inclined position described. An important feature contributing to the advantages flowing from the present invention, is the fact that the feelers are not only supported in position 80 above the plane of the warp threads, but are mounted in the side members of a feeler carrier, which is supported and operated for ready removal as a whole from operative position. In the preferred construction, the 85 side members of the feeler carrier include between them the entire series of drop wires and drop wire guides, so that no obstruction may be offered to the removal of the feeler carrier when it is desired to run the loom 90 without stopping, due to a warp fault or to change the warp in the loom.

What is claimed is:—

1. In a warp stop motion for looms, the combination of a series of drop wires adapted to be supported by the warp threads during weaving, a feeler having a detecting movement toward and from the drop wires above the plane of the warp threads, feeler actuating means, and connections between 100 the feeler and the feeler actuating means unobstructing movement of the feeler, at will from operative relation with the drop wires that the loom may be run without stopping due to a warp fault when the feeler is moved 105 from operative relation with the drop wires.

2. In a warp stop motion for looms, the combination of a series of drop wires adapted to be supported by the warp threads, a feeler having a detecting movement above 110 the plane of the warp threads toward and from the drop wires, a shaft from which the feeler derives its detecting movement, and connections between the feeler and said shaft unobstructing movement of the feeler 115 at will to an inoperative position relative to the drop wires when the loom is to be run without stopping due to a warp fault.

3. A warp stop motion for looms, comprising, in combination, a series of drop 120 wires, a feeler having a detecting movement above the plane of the warp threads, an actuator for the feeler, and connections between the feeler and actuator that enable the feeler to be lifted from operative position relative to the drop wires when the loom is to be run without stopping due to a warp fault.

4. In a warp stop motion for looms, the combination of a series of drop wires sup- 125

- ported by normal warp threads during weaving, a guide for the drop wires, a feeler having a detecting movement above the plane of the warp threads, an actuator for giving the feeler its detecting movement, and connections between the feeler and its actuator which enable the feeler to be lifted at will from its operative relation with the drop wires.
10. 5. In a warp stop mechanism for looms, the combination of a series of drop wires adapted to be supported by the warp threads during weaving, a guide passing through the drop wires, a feeler having a detecting movement toward and from the drop wires above the plane of the warp threads and supported for removal at will in a direction away from the plane of the warp threads and from operative relation with the drop wires that the loom may be run at times without stopping on account of a warp fault.
15. 6. A warp stop motion for looms, comprising, in combination, a series of drop wires, a feeler carrier, a feeler connected to the feeler carrier and having a detecting movement above the plane of the warp threads, an actuator for the feeler carrier, and connections between the actuator and feeler carrier unobstructing removal of the feeler carrier and feeler together from operative position that the loom may be run without stopping due to a warp fault.
20. 7. In a loom, the combination of a series of drop wires adapted to be supported by the warp threads during weaving, a feeler having a detecting movement above the plane of the warp threads toward and from the drop wires, a shipper, a train of mechanism between the feeler and shipper for stopping the loom when the detecting movement of the feeler is arrested by a drop wire, and means for supporting the feeler and unobstructing removal of the feeler at will from operative relation with the drop wires and actuator.
25. 8. A warp stop motion for looms, comprising, in combination, a series of drop wires adapted to be supported by the warp threads during weaving, a feeler having a detecting movement above the plane of the warp threads, a rock shaft for imparting feeler movements to the feeler, and connections intermediate the feeler and rock shaft which enable the feeler to be lifted from operative relation with the drop wires.
30. 9. In a warp stop motion for looms, the combination of a series of drop wires arranged in parallel rows, a feeler carrier, a series of feelers mounted on the feeler carrier above the plane of the warp threads, a rock shaft for reciprocating the feeler carrier, and connections between the rock shaft and feeler carrier constructed and arranged that the feeler carrier and feelers may be removed at will from operative position relative to the drop wires to enable the loom to be run without stopping due to a warp fault.
35. 10. In a warp stop motion, the combination of a bracket connected to each side of the loom frame, a feeler carrier mounted for reciprocating movement on said brackets, feelers carried by the feeler carrier above the plane of the warp threads, rows of drop wires, a rock shaft, and connections between the rock shaft and feeler carrier for actuating the feeler carrier from the rock shaft and permitting the feeler carrier and feelers to be moved from operative position when the loom is to be run without stopping due to a warp fault.
40. 11. In a warp stop motion for looms, the combination of a series of drop wires and drop wire guides, a feeler carrying frame provided with a feeler which has a detecting movement above the plane of the warp threads, and actuating means for effecting said detecting movement, the said feeler carrying frame and feeler being movable from operative position at will.
45. 12. In a warp stop motion for looms, the combination of a series of drop wires, a feeler carrying frame comprising the side members and a feeler extending between the side members, and means for supporting the side members with the feeler in operative position above the plane of the warp threads and free for unobstructed removal at will from operative relation to the drop wires.
50. 13. In a warp stop motion for looms, the combination of a series of drop wires arranged in parallel rows, drop wire guides, a feeler carrying frame comprising side members and feelers extending between the side members, means for supporting the feeler carrying frame with the feelers in operative relation to the rows of drop wires and unobstructed removal of the frame and feelers from such position that the loom may be run without stoppage due to a warp fault, and means for actuating the frame to impart a detecting movement to the feelers when they are in operative position.
55. 14. In a warp stop motion for looms, the combination of a series of drop wires, a feeler carrying frame comprising side members and feelers extending between the side members, a shaft, guides for supporting the side members that the feeler carrying frame may be lifted from operative position, and connections between the shaft and feeler carrying frame unobstructing movement of the frame to inoperative position.
60. 15. In a warp stop motion for looms, the combination of a series of drop wires arranged in parallel rows, drop wire guides, a feeler carrying frame comprising side members and feelers extending between the side members, means for supporting the side members for unobstructed movement from

- operative position, operating means for imparting detecting movements to the feelers, and detachable connections between the operating means and feelers that become detached when the feelers are moved from operative position.
16. In a warp stop motion for looms, the combination of a series of drop wires arranged in parallel rows and having enlarged portions facing in the same direction, feelers having a detecting movement toward and from the rows of drop wires above the plane of the warp threads, means for stopping the loom when the feeler detecting movement is arrested by a drop wire, an actuator for giving the feelers detecting movement toward and from the drop wires, and connections between the feelers and actuator that enable the feelers to be manually lifted from operative relation with the drop wires.
17. A warp stop motion for looms, comprising, in combination, a series of slotted drop wires adapted to be supported by the warp threads during weaving, a drop wire guide which is supported above the plane of the warp threads and passes through the slotted drop wires, a feeler supported above the plane of the warp threads, a feeler actuator for imparting reciprocating movements to the feeler in its feeling path above the warp threads, and connections between the feeler and feeler actuator which permit manual movement of the feeler in an upward direction away from operative relation with the drop wires to allow the loom to run at times without stopping on account of a warp fault and at other times to facilitate unobstructed removal of the drop wires and drop wire guides.
18. In a warp stop motion for looms, the combination of a series of drop wires adapted to be supported by the warp threads during weaving, a feeler carrier comprising side members, feelers extending between the side members, feeler braces engaging and bracing the feelers between the side members, the said side members, feelers, and feeler braces being connected together for removal as a unit from operative relation with the drop wires.
19. In a warp stop mechanism for looms, the combination of a series of drop wires adapted to be supported by the warp threads during weaving, a drop wire guide, a feeler having a reciprocating detecting movement above the plane of the warp threads towards and from the drop wires, means for reciprocating the feeler above the warp threads, and means for stopping the loom when the reciprocating movement of the feeler is arrested by a drop wire.
20. In a warp stop motion for looms, the combination of a series of drop wires adapted to be supported by the warp threads during weaving, a drop wire guide and a feeler both of which are positioned above the plane of the warp threads, means for reciprocating the detecting portion of the feeler in the horizontal plane passing through the drop wire guide, and means for stopping the loom when the feeler movement is arrested by a drop wire.
21. In a warp stop motion for looms, the combination of a series of drop wires arranged in parallel rows and supported in raised position by normal warp threads during weaving, a drop wire guide and a feeler for each row of drop wires and both arranged above the plane of the warp threads, means for imparting a detecting movement to the feelers toward and from the drop wire guides in the horizontal plane of the guides that an unsupported drop wire may act in the horizontal plane passing through the detecting portion of the feeler and the adjacent guide to arrest movement of the feeler, and means for stopping the loom when a feeler movement is arrested by a drop wire.
22. In a warp stop motion for looms, the combination of a series of drop wires having enlarged portions and arranged in two or more rows with the enlarged portions facing in the same direction, a feeler for each row of drop wires mounted above the plane of the warp threads, means for reciprocating the feelers toward and from their respective rows of drop wires above the warp threads, and means for stopping the loom when one of the feelers is arrested by a drop wire.
23. In a warp stop motion for looms, the combination of a series of drop wires adapted to be supported by the warp threads during weaving, a feeler having a detecting movement above the plane of the warp threads and supported in an inclined position relative to the lengthwise dimension of the drop wires that the space fore and aft of the loom occupied by a unit of the warp stop motion may be economized.
24. In a warp stop motion for looms, the combination of a series of drop wires arranged in two or more rows, a feeler for each row of drop wires mounted above the plane of the warp threads and supported in an inclined position relative to the lengthwise dimension of the drop wires to minimize the space fore and aft of the loom occupied by the stop motion, means for reciprocating the feelers toward and from their respective rows of drop wires above the warp threads, and means for stopping the loom when one of the feelers is arrested by a drop wire.
25. In a warp stop motion for looms, the combination of a plurality of feelers mounted in parallel relation above the plane of the warp threads back of the heddles, a row of drop wires for each feeler, a drop wire guide for each row of drop wires having a drop wire supporting portion in the horizontal plane of action of the feelers above the warp.

threads, means for reciprocating the feelers toward and from the supporting portion of the guide, and means for stopping the loom when one of the feelers is stopped by a drop 5 wire.

26. In a warp stop motion for looms, the combination of a series of drop wires, a drop wire guide which passes through all of the drop wires, a feeler supported in an inclined 10 position above the warp threads and having a drop wire engaging portion which acts in the horizontal plane of the drop wire guide, means for reciprocating the feeler to cause its drop wire engaging portion to move toward and from the drop wire guide, and means for stopping the loom when the feeler 15 is stopped by a drop wire.

27. In a warp stop motion for looms, the combination of a series of drop wires arranged 20 in parallel rows, a feeler for each row of drop wires supported in an inclined position relative to the vertical plane passing through a row of drop wires and each having a drop wire engaging portion, a guide 25 for each row of drop wires, and means for stopping the loom when a feeler is arrested by a drop wire.

28. In a warp stop motion for looms, a feeler carrying frame bodily movable to and 30 from operative position at will, and comprising side members, feelers extending between the side members and secured thereto at an inclination to the side members, and braces engaging the inclined feelers at points 35 between the side members.

29. In a warp stop motion for looms, the combination of drop wires arranged in parallel rows, a feeler carrier having side members, feelers extending between the side 40 members, above the plane of the warp threads, guiding supports for the side members from which they may be raised at will to lift the feelers heightwise of the drop wires out of operative position, and means 45 for moving the side members on said supports to impart detecting movements to the feelers when they are in operative position.

30. In a warp stop motion for looms, the combination of a series of drop wires arranged 50 in parallel rows, drop wire guides passing through the drop wires, a feeler carrier having side members, feelers extending between the side members above the plane of the warp threads, guiding supports 55 on which the side members rest and from which they may be raised at will to lift the feelers heightwise of the drop wires out of operative position, a rock shaft, and an arm extending from the rock shaft for operating the feeler carrier.

31. In a warp stop motion for looms, the combination of a bracket secured to each side of the loom, drop wire guides extending between the brackets, drop wires through 65 which the guides extend, guiding supports,

a feeler carrier having side members which rest upon the guiding supports, feelers extending between the side members above the plane of the warp threads, a rock-shaft and detachable connections between the rock-shaft and feeler carrier that the latter and the feelers may be removed at will when it is desired to run the loom without stopping due to a warp fault. 70

32. In a warp stop motion for looms, the combination of a bracket secured to each side of the loom, drop wire guides extending between the brackets, drop wires through which the guides extend, guiding supports beyond the ends of the drop wire guides, a feeler carrier having side members which rest upon the guiding supports, feelers extending between the side members above the plane of the warp threads, a rock shaft, and detachable connections between the rock 80 shaft and feeler carrier that the latter and the feelers may be removed at will when it is desired to run the loom without stopping due to a warp fault. 85

33. In a warp stop motion for looms, the combination of a bracket secured to each side of the loom, drop wire guides extending between the brackets above the plane of the warp threads, drop wires through which the guides extend, guiding supports at each side 90 of the loom, a feeler carrier having side members which rest and slide on said guiding supports, feelers extending between the side members above the plane of the warp threads, means for reciprocating the feeler 95 carrier, and connections between the feeler carrier and said means which becomes separated when the feeler carrier is raised from operative position. 100

34. In a warp stop motion for looms, the combination of a series of drop wires, drop 105 wire guides, a feeler supported above the warp thread and removable at will from operative relation with the drop wires, and means for supporting the drop wire guides 110 in guiding position that they may be bodily removed from the loom with the drop wires thereon when the feeler is removed from operative position.

35. In a warp stop motion for looms, a series of drop wires arranged in a row, a guide for the drop wires, a feeler carrier having side members, supports on which the side members of the feeler carrier slide, a feeler extending between the side members 115 above the plane of the warp threads, a rock shaft extending transversely of the loom frame, and connection between the rock shaft and feeler carrier for giving to the feeler carrier its sliding movement. 120

36. In a warp stop motion for looms, a series of drop wires arranged in a row, a guide for the drop wires, a feeler carrier having side members which are supported at each side of the loom, a feeler extending 125 130

between the side members above the plane of the warp threads, a rock shaft extending transversely of the loom frame, an arm extending from the rock shaft at each side of 5 the loom, and connections between each of said arms and the feeler carrier for reciprocating the carrier.

37. In a warp stop motion for looms, the combination of a series of drop wires 10 adapted to be supported by the warp threads when in normal condition during weaving, drop wire guides supported above the plane of the warp threads, and a brace above the plane of the warp threads for engaging and 15 holding the drop wire guides above the warp threads and preventing lateral deflection thereof.

38. In a warp stop motion for looms, the combination of a series of drop wires 20 adapted to be supported by the warp threads when in normal condition during weaving, drop wire guides supported above the plane of the warp threads, and a brace above the plane of the warp threads having notches 25 in its upper edge for receiving and holding the drop wire guides above the warp threads and preventing lateral deflection thereof.

39. In a warp stop motion for looms, the combination of a series of drop wires 30 adapted to be supported by the warp threads when in normal condition during weaving, drop wire guides supported above the plane of the warp threads, and adjustable braces for the drop wire guides supported above 35 the plane of the warp threads for adjustment into converging relation to conform with the convergence of the warp threads toward the front of the loom.

40. In a warp stop motion for looms, the combination of a series of drop wires 40 adapted to be supported by the warp threads, a drop wire guide and a feeler above the plane of the warp threads, a warp support below the plane of the warp threads, and 45 means for vertically adjusting the warp support.

41. In a warp stop motion for looms, the combination of a series of drop wires 50 adapted to be supported by the warp threads, a drop wire guide and a feeler above the plane of the warp threads, a warp support below the plane of the warp threads, and means for adjusting the warp support toward and from the plane of the drop wire 55 guide and feeler.

42. In a warp stop motion for looms, the combination of a series of drop wires, a drop wire guide and feeler both above the plane of the warp threads, a warp support 60 below the plane of the warp threads and adjustable toward and from the guide and feeler, a feeler actuator movable with the warp support as it is adjusted, and connections between the feeler and actuator for 65 maintaining the amplitude of feeler move-

ment unchanged when the warp support is adjusted.

43. In a warp stop motion for looms, the combination of a series of drop wires, a 70 feeler supported above the plane of the warp threads, an arm for actuating the feeler, and a pin and slot connection between the feeler and arm arranged to be disengaged when the feeler is removed from operative position. 75

44. In a warp stop mechanism for looms, the combination of a series of drop wires adapted to be supported by the warp threads during weaving, a feeler having a detecting movement above the plane of the warp 80 threads, actuating means for giving the feeler its detecting movement above the plane of the warp threads, connections between the feeler and its actuating means unobstructing removal of the feeler from its 85 operative relation with the drop wires at will, and means on the loom for supporting the feeler when removed from its operative position.

45. In a warp stop mechanism for looms, 90 the combination of a series of drop wires adapted to be supported by the warp threads during weaving, a drop wire guide which passes through the drop wires of a row above the plane of the warp threads, means for 95 detachably holding the drop wire guide in its guiding position above the plane of the warp threads, a feeler having a reciprocating detecting movement above the plane of the warp threads, and supported for unobstructing removal of the drop wires and drop wire 100 guide together.

46. In a warp stop mechanism for looms, the combination of a series of drop wires 105 adapted to be supported by the warp threads during weaving, a drop wire guide, supports for detachably supporting the drop wire guide above the plane of the warp threads, a feeler having a reciprocating movement above the plane of the warp threads, and 110 supported for unobstructed removal of the drop wires and drop wire guides, an actuator for reciprocating the feeler above the plane of the warp threads, and a train of mechanism for stopping the loom when the reciprocating movement of the feeler is arrested by a drop wire. 115

47. In a warp stop mechanism for looms, the combination of a series of drop wires 120 adapted to be supported by the warp threads during weaving, a feeler having a detecting movement with relation to the drop wires above the plane of the warp threads, a feeler actuator for imparting detecting movement to the feeler, and means connecting the feeler and actuator permitting unobstructed detachment of the feeler and actuator in a vertical direction whereby the loom may be run at will without stopping 125 due to a warp fault. 130

48. In a warp stop motion for looms, the combination of a series of drop wires adapted to be supported by the warp threads during weaving, a feeler having a detecting movement with relation to the drop wires, feeler actuating means for giving the feeler its detecting movement, and connections be-

tween the feeler and the actuating means that permit unobstructed detachment in a vertical direction of the feeler from operative relation to the actuator. 10

In testimony whereof, I have signed my name to this specification.

EDWARD S. STIMPSON.
